United States Patent Office.

CHARLES F. WOODRUFF, OF NEWBERN, TENNESSEE.

Letters Patent No. 80,696, dated August 4, 1868.

IMPROVED EXCAVATOR.

The Schedule referred to in these Letters Patent and making part of the same.

TO ALL WHOM IT MAY CONCERN:

Be it known that I, CHARLES F. WOODRUFF, of Newbern, in the county of Dyer, and State of Tennessee, have invented a new and improved Excavator; and I do hereby declare that the following is a full, clear, and exact description of the construction and operation of the same, reference being had to the accompanying drawings, making a part of this specification, in which—

Figure 1 is a side elevation.

Figure 2 is a top view.

This invention relates to that class of excavators in which a revolving scraper is employed, and consists in so adjusting such scraper, and the means for operating it, that it can be worked more conveniently than heretofore.

In the drawings, A A represent the draught-bars, united by a cross-bar or round, a, and supporting, at their central portion, b, the body, B, of the instrument, their rear portion extending upward and backward, and terminating in handles C C, which are connected by a round, c.

The body, B, of the excavator is hung to the draught-bars or frame upon journals e e, so that it can be rotated upon such journals. Its sides are formed of two diamond-shaped boards or plates, D D, connected together by cross-bars or rounds, d d' d'' d''', and by scraper-blades s s, constructed and arranged as seen clearly in the drawings. Its bottom is composed of two plates or boards, F F', hinged along one edge at f f, and so that when one side of the body B is up, the inner edges of the plates F F' rest upon the round, d, and when the other side is up, such edges rest upon the opposite round, d'', as seen in fig. 1.

The plates F F' are hung loosely upon their pivots or hinges, so that as the body of the instrument is rotated they drop against the lower round, as seen in outline in fig. 1, forming a box, into which the dirt excavated by the cutting-blades s or s' is received, and in which it is retained until, by the rotation of the box, it is delivered, and the box is set again to receive another load.

In order to afford a convenient means for fixing the body B firmly in position, so that it cannot be rotated except at the desire of the operator, and so that when he wills he can allow it to rotate freely, I employ an apparatus, which I will now proceed to explain. It consists of a ratchet, w, fixed to the side of the body B upon the journal e, and having a pawl, p, pivoted to the draught-bar A, and working in connection with it, as seen in fig. 1. When the pawl is engaged with the ratchet, the body B cannot turn on its axis, but when disengaged, the body is free to turn, and will at once discharge its contents.

The pawl is engaged or disengaged at pleasure, by means of a lever, M, which is pivoted upon the journal e, and extends alongside of the handles C, terminating in a handle, m. The short arm of the lever lies under the pawl p, and serves to throw the latter up and disengage it from the ratchet. An arm or hook, n, extends from the short arm up over the pawl p, and serves to draw the latter down and cause it to engage with the ratchet again. Thus, by throwing the handles m m forward or up, the pawl is caused to engage and prevent the body B from rotating; and by reversing the action of the handles m m, the pawl is disengaged, and the body B left free to turn and discharge its load. The handles m are within easy reach of the handle C, by which the operator holds and governs the instrument. The apparatus may be employed on each side of the instrument, or not.

Having thus described my invention, what I claim as new, and desire to secure by Letters Patent, is—

1. In a revolving scraper or excavator, the combination of the swinging plates F F' and the rounds d d'', or their equivalents, substantially as and for the purposes specified.

2. The combination of the lever M, having the handle m and the hook n, with the pawl p, ratchet w, and body B, when the parts are constructed to operate substantially in the manner and for the purpose specified.

To the above specification of my improvement I have signed my hand, this 22d day of May, 1868.

C. F. WOODRUFF.
